Primary Examiner — Austin Murphy(74) *Attorney, Agent, or Firm* — Dennis R. Haszko**CLAIM**

The ornamental design for a cartridge for coating film transfer tool, as shown and described.

DESCRIPTION

FIG. 1 is a perspective view of the cartridge for coating film transfer tool showing the design;

FIG. 2 is a front view thereof;

FIG. 3 is a rear view thereof;

FIG. 4 is a plan view thereof;

FIG. 5 is a bottom view thereof;

FIG. 6 is a right side view thereof;

FIG. 7 is a left side view thereof;

FIG. 8 is a cross-sectional view thereof taken along line A-A of FIG. 2;

FIG. 9 is a front view thereof;

FIG. 10 is a cross-sectional view thereof taken along line B-C-D of FIG. 9;

FIG. 11 is a cross-sectional view thereof taken along line E-F-G-H of FIG. 9; and,

FIG. 12 is a front view thereof without a tape mounted therein.
